UNITED STATES PATENT OFFICE.

ARRON R. CHISHOLM, OF EAST ORANGE, NEW JERSEY.

SUSPENSORY BANDAGE.

Application filed April 30, 1926. Serial No. 105,654.

The invention relates to suspensories having a sack suspended from a belt, and is based on Letters Patent to me dated Nov. 4, 1919, No. 1,320,737.

5 The object of the present invention is to provide sack-supporting means which shall conform to and lie in close contact with the body of the wearer in all positions of the latter and thus insure the proper functioning of the bandage and avoid the danger of 10 displacement due to such changes.

Another important object is to provide means for detachably joining the sack to the supporting belt, so arranged that the 15 metal portions of such joining means and also the adjustable fastening for the belt-ends are held out of direct contact with the flesh of the wearer.

The invention consists in certain novel 20 features of construction and arrangements of parts by which the above objects are attained, to be hereinafter described and claimed.

The accompanying drawings form a part 25 of this specification and show two forms of the invention as it has been carried out in practice.

Figure 1 is a front elevation of a preferred form of the bandage, in which the 30 sack is detachable.

Figure 2 is a horizontal section taken on the line 2—2 in Figure 1.

Figure 3 is an elevation corresponding to a portion of Figure 1, showing a form in 35 which the sack is permanently attached.

Similar reference numerals indicate the same parts in all the figures.

All the parts supporting the sack 5 are of inelastic webbing woven in the direction 40 of their lengths and adapted to resist lateral distortional strains.

The sack 5 is supported from a transverse cross-piece 6 having at its mid-length a vertically extended upright member 7. The 45 cross-piece 6 is double, see Figure 2, and receives between its parts the ends 8 and 9 of two diagonally arranged members 10 and 11 forming the belt which is adapted to extend over the hips of the wearer and 50 across the back and to follow the lines of the groins but not to lie in the waist line.

The belt member 10 carries a buckle 12 arranged to engage the longer belt member 11, and the metal of the buckle is held out 55 of contact with the body by the projecting end 13 of the shorter belt member 10.

From the upper portion of the upright member 7 and extending oppositely therefrom are two braces 14 which are attached by lines of stitches 15 to the belt members 60 10 and 11, as shown.

The braces 14 thus form acute angles with the belt members and tend to aid in resisting any tendency of the structure to distortion. The upright member 7 is in the form 65 of a loop receiving between its two limbs the ends of the braces 14 and also the cross-piece 6, all joined by the lines of stitches 23.

In the form shown in Figures 1 and 2 the cross-piece 6 has at each end a depending tab 16, each equipped with the stud portion 17 of a snap fastener, and each end of the cross piece carries a similar stud portion 18. At separated points on the upper 70 margin of the sack 5 are two loops 19, and the outer portion of each loop carries the socket portions 20 of snap fasteners adapted to engage the above described stud portions. Thus arranged the sack is detachably secured and may be removed for cleansing, 75 renewal, or the substitution of a different sack.

It will be noted that contact of the metal 80 of the socket portions 20 with the body of the wearer is prevented by the interposition of the inner portions of the loops 19.

In the form shown in Figure 3 the tabs 85 21 are shorter than the tabs 16 above described and are permanently fastened to the sack 5 by the stitches 22.

The arrangement of the cross-piece 6 and its upright member 7, together with the belt ends 8 and 9 and braces 14 is such as to insure that the sack hangs in the proper position regardless of the girth of the wearer. 90 The location of the sack is the same in all sizes and shapes of figures, and is unaffected by these factors because the sack hangs below the abdomen in all cases, due to the manner of tieing or bracing the several 95 parts of the support and the material employed.

The web members of the structure lie flat 100 against all the body-surfaces and follow the natural lines of the body so that when properly positioned there is no tendency to ride up or sag down or otherwise change in position regardless of body movements.

Importance is attached to the fact that 110 the members 14 extend downwardly at an angle from their points of attachment with the members 11 and 12, with their other

ends joined to the upper end of the upright 7 in close proximity to the attachment of the members 8 and 9 with the cross-piece 6, as by this means the supporting means 5 will have a tendency to depend and closely contact with the body of the wearer at a point in proximity to the sack, with the result that the sack at all times hangs below the abdomen and is held in proper position 10 suspended at a point below the pit of the stomach.

I claim:—

A device of the character described comprising a sack, a cross-member having means 15 for supporting the sack, a relatively short

upright member secured to said cross-member, belt members secured to opposite ends of said cross-member, and inclined brace members having their adjacent ends secured to the upper end of said upright member, 20 said brace members being fixedly connected with the belt members and disposed at an acute angle to the belt members and overlapping the latter for a greater portion of their length, all of said members being of 25 flexible inelastic webbing.

In testimony that I claim the invention above set forth I affix my signature hereto.

ARRON R. CHISHOLM.
